UNITED STATES PATENT OFFICE

JUSTIN W. GRIESS, OF CINCINNATI, OHIO

SPRAYING MACHINE

Application filed June 28, 1928, Serial No. 288,368. Renewed July 1, 1931.

In manufacturing fancy leathers I have found that especially pleasing color effects and surface finishes can be produced by spraying coating materials, such as lacquers, on the hides or skins. However, the practice of such a process on a commercial scale involves considerable difficulties in producing uniform results, maintaining the desired control of the process at all times, and particularly in avoiding the production of blemished goods due either to an uneven distribution of the coating material or to the presence of wrinkles in the hides or skins during the application of such material.

The present invention relates to spraying machines of a type designed especially for use in this work although adapted also for use in coating materials which can be handled in essentially the same manner as skins or hides. It is the chief object of the invention to devise a machine in which the spraying operation can be performed rapidly and efficiently, in which the desired control can be maintained, and with which the labor cost involved in producing leathers by this process will be substantially reduced. The invention also aims to facilitate the handling of the hides and skins and to improve the means for supporting the skins while they are being sprayed. For convenience the material undergoing treatment will be herein referred to as "skins", this term being used to include skins, hides, sides, or other material which the machine is adapted to handle.

The nature of the invention will be readily understood from the following description when read in connection with the accompanying drawings, and the novel features will be particularly pointed out in the appended claims.

In the drawings,

Figure 1 is a view chiefly in side elevation of a machine embodying the present invention;

Figure 2 is a plan view of the machine shown in Fig. 1;

Fig. 3 is a perspective view of one of the spray guns used in Figs. 1 and 2, this view also illustrating the means for operatively supporting the spray gun; and

Fig. 4 is a plan view showing another spray gun arrangement.

The machine shown includes a large drum 2 having an approximately cylindrical fomorous wall 3. Preferably this drum is mounted to rotate about a vertical axis, and it is connected by a conduit or wind trunk 4 to the intake end of a large blower or pump 5 which is adapted to maintain a partial vacuum in the drum. It will be clear, therefore, that skins 6 placed against the outer wall 3 of the drum will be held on said wall by the suction maintained within the drum. This arrangement facilitates the placing of the skins in position for the spraying operation or their removal from this position, and makes it very easy for the attendant to stretch the skins smoothly on the surface of the drum and to avoid the presence of wrinkles. The holes in the drum should be of sufficient size to cause the suction to hold the skins firmly in position but still not large enough to produce any depressions in the outer surface of the skin. I have found that holes approximately three-sixteenths of an inch in diameter produce entirely satisfactory results.

The wall 3 of the drum 2 preferably is at least six feet in width so that several relatively large skins can be held at one time on the outer surface of the drum in position for spraying. The coating material is applied by any suitable form of spraying apparatus. As shown, several spray guns 7 of a common form are mounted at points spaced apart by substantially equal distances circumferentially around the drum 2, each gun being equipped with the usual paint pot or container 8 to hold a supply of the coating ma-

terial, and having a hose connection 9, Fig. 3, for conducting air under pressure to the gun. Guns of any one of the several forms known commercially may be used.

5 The guns are mounted for vertical traversing movement and for this purpose each gun is supported on a carriage 10, best shown in Fig. 3, which is mounted on two vertical rods 12—12, these rods forming a track for the 10 travel of the carriage.

Power driven mechanism is provided for producing the traversing movement of the guns. Referring to Figs. 1 and 2, it will be seen that the carriages 10—10 of the two guns 15 7—7 mounted at the front of the machine, or nearest the observer, are connected by a chain 13 which runs over sprocket wheels 14—14' above the drum. Another chain 15 connects the two carriages 10—10 just referred to and 20 runs over sprocket wheels 16—16 located below the drum. It will thus be evident that if the sprocket wheel 14 is driven the two spray guns 7—7 just referred to will be moved simultaneously but in opposite directions on their tracks 12—12. The two spray guns at 25 the back of the machine are connected in the same manner by chains, the upper chain being shown at 17, Figs. 1 and 2, and running over sprocket wheels 18—18'. The two sprocket wheels 14 and 18 are mounted fast on a horizontal shaft 19 carrying a sprocket wheel 20 which is driven through a chain 21 from another sprocket wheel 22 fast on the shaft 23. A reversible mechanism is 30 provided for driving this shaft 23. This mechanism comprises two pulleys 24 and 25 both fast on the shaft 23 and an intermediate pulley 26 which is loose on said shaft. The pulley 24 is driven by an open belt 27, while the pulley 25 is driven by a cross belt 28, both of these belts running over and being driven by a wide-faced pulley 29 on the driving shaft 30. A belt shifter 31 controls the position of both belts 27 and 28.

35 It will be clear that when the belt 27 is driving the pulley 24 the chains 17 and 13 will be driven in one direction, the cross belt 28 at this time being on the loose pulley 26. When the shifter 31 is moved to shift the belts into the position shown in Fig. 2, the cross belt 28 then will drive the pulley 25, the open belt 27 at this time driving the loose pulley 26 so that the direction of movement of the chains 17 and 13 will, at 40 this time, be reversed.

In order to produce this reversal automatically the belt shifter 31 is mounted on a lever 32, one end of which is connected by a rod 33 to a lever 34 having an end 45 located in the path of travel of a lug 35 which is adjustably secured on the chain 17. The opposite end of the lever 32 is connected by a rod 36 to a lever 37 having an end portion located in the path of travel of another lug 38 also adjustable on the chain 17.

Assuming that the lever 34 has just been moved into the position shown in Fig. 2 by the lug 35 and that the chains 17 and 13 are now travelling in the directions indicated by the arrows, it will be evident that 50 when the lug 38 strikes the lever 37 it will operate through the belt shifter 31 to reverse the direction of travel of the chain. Another reversal will occur when the lug 35 strikes the lever 34 and these movements will continue so long as the machine is in operation. Obviously the points at which each reversal of movement will take place can be predetermined by adjusting the lugs 35 and 38 on the chain 17. This adjustment also will control the length of stroke of each gun 7 since all the guns are driven by the same mechanism.

In order to carry the skins past the path of travel of the guns the drum 2 is given a relatively slow rotary movement. For this 55 purpose a worm gear 40 is secured to the drum and is driven by a worm 41 mounted fast on the driven shaft 42 of a variable speed mechanism of a well known type, which is indicated in general at 43. Power for operating this mechanism may be derived from an electric motor 44, Fig. 2. The variable speed mechanism includes two cone pulleys 45 and 46 connected by a belt or chain 47 having tapered sides, the end pieces of each of the pulleys 45 and 46 being adjustable toward and from each other so that the effective diameters of the pulleys may be adjusted at will.

It will be clear that the amount of coating material applied to any given hide will depend upon the adjustment of the spray in the gun, the rate of traversing movement of the gun, and the rate at which the drum 2 carries the skin past the path of travel 100 of the gun. All of these factors can be adjusted so that the amount of spray applied to each hide will be controlled very accurately.

For the purpose of permitting an adjustment of the distance between the end of each spray nozzle and the foraminous wall 3, each gun is supported in a holder 49, Fig. 3, which is adjustably mounted on a rod 50 fixed in the carriage 10. Preferably the holder 49 includes a split clamp which permits an angular adjustment of the gun 7 in a vertical plane, the gun being secured in its adjusted position by a bolt 51, Fig. 3. This adjustment enables the operator or attendant to set the gun so that the spray will strike the skin at the desired angle which often is very important in order to produce the desired results.

In using the machine the attendants place 115 the skins 6 against the foraminous wall 3 and smooth them out, the suction thereafter holding the skins securely in position for the spraying operation. As the drum revolves slowly each skin is brought into the field of 120

operation of the spray produced by one of the guns 7, and it receives a coating of material, the thickness of the coating being predetermined in the manner above described. 5 If it is desired to apply more than one coat, each skin can be subjected to the action of the sprays discharged from two or more guns. Different shades or colors can be used in successive guns if desired. This machine 10 thus reduces very substantially labor involved in coating skins with paint, lacquer, or liquid of any character. The mounting of the skins in position for the spraying operation and their removal from said position 15 is facilitated, and the difficulties heretofore experienced in supporting a skin smoothly for spraying are greatly reduced. By properly proportioning the movements of the spray gun and the drum, the coating material 20 can be applied very uniformly so that the production of streaked and blemished skins is substantially eliminated. It will be observed that each spray gun is maintained at a substantially fixed distance from the surface 25 of the skin at all times which is an important factor in producing uniform results, especially in spraying coloring materials which are dissolved in highly volatile solvents. The penetration of the coloring material 30 into the skins also is increased by the suction and the drying of the coating is facilitated by the strong current of air which flows across the surface and around the edges of the skins. Many of the coloring materials used 35 are applied in solution in volatile solvents which have toxic properties or are explosive. When such materials are used in the machine shown these solvents are carried directly away from the operator and out of the room so that 40 any accumulation of them where they must be breathed by the operator, or where they would produce a fire hazard, is avoided.

It is entirely feasible to mount a plurality of spray guns on a single carriage and such 45 an arrangement is shown in Fig. 4 in which two guns 7'-7' are supported on the holder 49'. Such an arrangement is desirable under some circumstances.

While I have herein shown and described 50 a preferred embodiment of my invention, it will be understood that the invention may be embodied in other forms without departing from the spirit or scope thereof.

Having thus described my invention, what 55 I desire to claim as new is:

1. In a spraying machine, the combination 60 of a support for holding the entire area of a skin simultaneously in position for the spraying operation, said support including a foraminous wall and means for applying suction to one surface of said wall to hold the entire area of a skin against the opposite surface for movement therewith, apparatus for spraying material on a skin so supported, means on which said support is mounted for

movement to carry the skin past said apparatus, and power driven mechanism for traversing said spraying apparatus.

2. In a spraying machine, the combination 70 of a rotary drum mounted to revolve about a vertical axis and having a foraminous wall for supporting the entire area of a skin simultaneously in position to be sprayed, means for creating suction in said drum to hold the entire area of a skin against the outer surface of said wall for movement therewith, apparatus for spraying material on a skin so supported, power driven mechanism for traversing said spraying apparatus, and means for moving said support to carry the skin past the path of travel of said spraying apparatus.

3. In a spraying machine, the combination 75 of a rotary drum mounted to revolve about a vertical axis and having a substantially cylindrical foraminous wall for supporting the entire area of a skin simultaneously in position to be sprayed, means for creating suction in said drum whereby the entire area of a skin placed against the outer surface of said wall will be held thereon by the suction, apparatus for spraying material on a skin so supported, and means for relatively moving said drum and apparatus to traverse 80 the spray across the skin.

4. In a spraying machine, the combination 85 of a rotary drum having a substantially cylindrical foraminous wall for supporting the entire area of a skin simultaneously in position to be sprayed, means for creating suction in said drum whereby the entire area of a skin placed against the outer surface of said wall will be held thereon by the suction, apparatus for spraying material on a skin so supported, means for supporting said apparatus for traversing movement at a fixed distance from said wall, and mechanism for 90 rotating said drum to carry the skin past said apparatus.

5. In a spraying machine, the combination 95 of a rotary drum mounted to revolve about a vertical axis and having a substantially cylindrical foraminous wall for supporting the entire area of a skin simultaneously in position to be sprayed, means for creating suction in said drum whereby the entire area of a skin placed against the outer surface of said wall will be held thereon by the suction, a gun for spraying material on a skin so supported, a track on which said gun is mounted for reciprocating movement at a substantially fixed distance from said foraminous wall, mechanism for reciprocating said apparatus on said track, and additional mechanism for rotating said drum to move said wall and a skin supported thereon past the path of travel of said gun.

6. In a spraying machine, the combination 100 of a rotary drum mounted to revolve about a vertical axis and having a substantially

cylindrical foraminous wall for supporting the entire area of a skin simultaneously in position to be sprayed, means for creating suction in said drum whereby the entire area of a skin placed against the outer surface of said wall will be held thereon by the suction, a plurality of spray guns for spraying material on skins mounted on said wall, means supporting said guns for movement in paths spaced from each other and at substantially fixed distances from said wall, and mechanism for revolving said drum.

7. In a spraying machine, the combination of a rotary drum mounted to revolve about a vertical axis and having a foraminous wall for supporting the entire area of a skin simultaneously in position to be sprayed, means for creating suction in said drum to hold the entire area of a skin against the outer surface of said wall, apparatus for spraying material on a skin so supported, and power driven mechanism for rotating said drum to carry the skin past said spraying apparatus, said mechanism being adjustable to vary the speed of rotation of said drum.

8. In a machine of the character described, the combination of a rotary drum having a substantially cylindrical foraminous wall, means supporting said drum for rotation about a vertical axis, means for creating suction in said drum whereby a skin placed against the outer surface of said wall will be held thereon by the suction, a plurality of spray guns mounted at points spaced apart circumferentially of said drum and arranged to spray material on the skins supported on said wall, tracks on which said guns are mounted for vertical traversing movement, power driven mechanism for traversing said guns, and mechanism for revolving said drum about its axis.

9. In a spraying machine, the combination of a suction support for holding a plurality of skins simultaneously in position for the spraying operation, a plurality of spray guns for spraying material on the skins mounted on said support, means supporting said guns for movement in fixed paths spaced from each other, a reversible mechanism for driving all of said guns to give them a traversing movement simultaneously, and means for automatically reversing the action of said driving mechanism, the last named means being adjustable to vary the length of the traversing stroke of the guns.

10. In a machine of the character described, the combination of a rotary drum having a substantially cylindrical foraminous wall, means supporting said drum for rotation about a vertical axis, means for creating suction in said drum whereby a skin placed against the outer surface of said wall will be held thereon by the suction, a plurality of spray guns mounted at points spaced apart circumferentially of said drum and ar-

ranged to spray material on the skins supported on said wall, tracks on which said guns are mounted for vertical traversing movement, a reversible power driven mechanism connected with said guns to move them simultaneously on their tracks, means for automatically reversing the operation of said power driven mechanism, the last named means being adjustable to vary the length of stroke of the guns, and adjustable power driven mechanism for revolving said drum about its axis.
